EXPANSION SHIPPING CONTAINER

Herald T. Snyder, Seattle, Wash., assignor to
Tom W. Holman, as trustee for an owner cor-
poration to be organized

Application May 29, 1941, Serial No. 395,817

2 Claims. (Cl. 229—62)

My invention relates to an expansion shipping container. More particularly, my invention relates to an envelope-like device for use in connection with shipping or mailing of merchandise.

A characteristic feature of my invention is that it provides a device which is expandable so that the device will accommodate merchandise items, which individually vary in size over a substantial range.

In the shipping departments of shops, factories, laboratories, wholesale and retail establishments, and similar places, there is an urgent need for shipping and mailing containers of various sizes due to the individual sizes of the various items shipped.

Despite the fact that many shipping departments carry numerous sizes and shapes of shipping containers, it is considered commercially impractical to carry sizes to fit every article which may pass through said shipping department. It is, therefore, standard practice today to install racks holding rolls of corrugated paper board and to cut individual strips from these rolls of paper board and wind the same around the article and thus form the covering or shipping container of a particular shaped article.

It is an object of my invention to provide an expandable shipping container so that a single size of envelope may be used as a shipping container for articles varying over a substantial range in size.

It is a further object of this invention to provide two face members having positioned therebetween edge members and an end member which are folded inwardly and between said face members, so that the article containing capacity of my envelope will readily expand much beyond its flat or knocked-down capacity.

It is a further object of my invention to provide a fold-over flap connected to one face member and having a plurality of spaced apart connecting means which cooperate with connecting means carried by the other face member to provide for various capacities of my shipping envelope.

It is a further object of my invention to provide a shipping container which will reduce the bulk of each individual shipment and at the same time provide a device which has a capacity to envelop articles over a considerable range of sizes.

It is a further object of my invention to provide for the saving of time which would otherwise be necessary in selecting the proper size of container or in making containers for individual articles.

It is an object of my invention to provide an

envelope for use as a shipping container, which envelope will have particular advantages when used for enveloping articles as silk stockings, handkerchiefs, and similar soft and pliable articles. A particular advantage in such cases will be that parties handling such merchandise in envelopes of my invention will not have the tendency to reduce the size of the package by rolling, folding and the like and therefore the merchandise will be much better protected when shipped in or when handled while contained in an envelope of my invention.

The above mentioned general objects of my invention, together with others inherent in the same are attained by the device illustrated in the following drawing, the same being a preferred exemplary form of embodiment of my invention, throughout which drawing like reference numerals indicate like parts:

Fig. 1 is a perspective view of a device embodying my invention in collapsed or knocked-down form;

Fig. 2 is a perspective view showing a device embodying my invention in somewhat expanded form;

Fig. 3 is a perspective fragmentary view showing the flap member of my invention folded upon itself and with the fastening means secured;

Fig. 4 is a sectional view taken substantially on broken line 4—4 of Fig. 2 and showing by dash lines an article disposed within the shipping container of my invention;

Fig. 5 is a sectional view taken substantially on broken line 5—5 of Fig. 2; and

Fig. 6 is a perspective view of a fragment of a device embodying my invention and showing particularly the bottom portion of the envelope.

Referring to the drawing, I provide two oppositely disposed face members 10 and 11. Edge members 12 and 13 are connected to said face members 10 and 11 and are folded inwardly and between said face members 10 and 11 along crease lines 22 and 23. The end portion 14 is folded inwardly and between the two face members 10 and 11 and along crease line 24. Also the end member 14 connects between said face members 10 and 11 and forms the bottom portion of the envelope embodying my invention.

Extensions 15 are provided on each of the edge members 12 and 13. When these extensions are folded inwardly, they cooperate with the flap 16 in providing a closure for the envelope and particularly so when the envelope is expanded to its full capacity. The flap member 16 is provided with a plurality of spaced apart openings or holes

18 which are preferably provided with reinforcing means 20 thereabout. As shown in the drawing it is only necessary to provide such means 20 about the outermost opening 18. Preferably the flap member 16 is provided with a plurality of score lines 17 to aid in the folding of the flap along said score lines 17. The holes 18 are so positioned that when the flap is folded along the score lines 17, the holes 18 are then in registration. Therefore, whether one fold is made or whether more than one fold is made, the holes 18, which are in superposed relation because of such fold or folds, will be in registration so such holes 18 may be caused to cooperate with the fastener means 19 to fasten the envelope. The fastener 19 may be of any usual construction and in the drawing I have shown the same as a metallic member generally known on the market as a "Columbian clasp." A gummed portion 21 is provided on the face member 10 so that flap 16 may be glued to said face member 10 as well as mechanically secured thereto by the clasp or fastener 19. While the usual practice is to provide on the flap the gummed surface or glued portion, which will adhere upon wetting, in my invention I employ the gummed portion 21 on the face member 10 so that the flap 16 may be adhered thereto by gluing regardless of the extent of the folding of said flap 16.

In the use of devices embodying my invention, the shipping clerk will be provided with a number of sizes of such devices. Obviously, my device may not be expanded to contain articles of every size, but it is subject to expansion so that it will contain articles over a very substantial range and eliminate the need for the many sizes of envelopes now carried by the shipping clerks. The shipping clerk will therefore select an envelope embodying my invention where the range of capacity thereof meets the size of the article to be shipped. Thereafter the face member 10 will be moved somewhat upwardly to the extent necessary to contain the article within the envelope. Then the extensions 15 will be folded inwardly and the flap 16 will be folded to the extent desired along a score line or lines 17 so that an opening or hole 18 will be moved in registration with the fastener or clasp 19. In accordance with the usual practice, the clasp 19 will be moved out of the flattened position shown in Fig. 2 so that the prongs of said clasp 19 may be projected through an opening 18. The opening 18 may be composed of one or more of said holes 18, depending upon the extent of folding of the flap 16. Then the prongs of said clasp 19 are flattened or moved into securing position. Of course if the flap 16 is to be glued to the face member 10, the portions 21 will be wetted before the engagement of the clasp 19.

In Fig. 3 I have shown the device of my invention in a position it would assume when containing a substantially flat article so that the flap 16 has been folded on two score lines 17 and the three holes 18 are shown in registration and the prongs of the clasp 19 have been projected through said holes 18. In Fig. 4 I have shown, by dash lines, a larger article contained within the device of my invention so that only one of the holes 18 is presented to the fastener or clasp

19 and the clasp 19 is shown as being sealed or closed.

While I have shown three score lines 17 in the drawing of my invention, it is to be expressly understood that this is a mere illustration of a plurality of score lines. Similarly the three holes 18 which are shown are to be considered as mere illustration of a plurality of holes. Again, while I have shown a fastener means 19 generally termed a "Columbian clasp" which interfits with holes 18, it is to be expressly understood that other well known means and forms of clasps available on the market may be used in my invention.

Obviously, changes may be made in the form, dimensions and arrangements of the parts of my invention, without departing from the principle thereof, the above setting forth only a preferred form of embodiment.

I claim:

1. A device of the class described, comprising two face members; two edge members connected with said face members and folded inwardly and between said face members; an end member connected with said face members and folded inwardly and between said face members; fastener means carried by one face member; an adhesive strip on said one face member positioned adjacent said fastener means; and an other end member connected to the other face member and comprising a flap scored to provide a plurality of juxtapositioned folds and having an opening in each fold positioned in registration when the folds are juxtapositioned and which openings are detachably connectable with said fastener means carried by said one face member, whereby the portion of the lower surface of said other end member, which is positioned adjacent said one face member by said fastener means, may be adhered thereto by said adhesive strip which is carried by said one face member.

2. A device of the class described, comprising two face members; two edge members connected with said face members and folded inwardly and between said face members; an end member connected with said face members and folded inwardly and between said face members; fastener means carried by one face member; an adhesive strip on said one face member positioned adjacent said fastener means; an other end member connected to the other face member and comprising a flap scored to provide a plurality of juxtapositioned folds and having an opening in each fold positioned in registration when the folds are juxtapositioned and which openings are detachably connectable with said fastener means carried by said one face member, whereby the portion of the lower surface of said other end member, which is positioned adjacent said one face member by said fastener means, may be adhered thereto by said adhesive strip which is carried by said one face member; and extension means; carried by said edge members at the end portions thereof which are adjacent said other end member, and extending beyond said face members, whereby said extension means may be folded with said other end member and cooperate therewith as closure means.

HERALD T. SNYDER.
